BENGT M. W. HANSON, OF HARTFORD, CONNECTICUT, ASSIGNOR TO PRATT & WHITNEY COMPANY, OF NEW YORK, N. Y., A CORPORATION OF NEW JERSEY.

CHUCK.

1,372,287.

Specification of Letters Patent. Patented Mar. 22, 1921.

Application filed July 31, 1918. Serial No. 247,685.

To all whom it may concern:

Be it known that I, BENGT M. W. HANSON, a citizen of the United States, residing at Hartford, in the county of Hartford and 5 State of Connecticut, have invented certain new and useful Improvements in Chucks, of which the following is a specification.

The invention relates especially to chucks of the magnetic type, and the object of the 10 invention is to provide a magnetic chuck having improved means whereby work can be secured mechanically to the chuck either in association with the magnetic action or independently thereof, and whereby stops, 15 guides or fixtures may be secured to the chuck to assist in the location of work thereon. In the accompanying drawing I have illustrated the embodiment of the invention which I now deem preferable, but it will 20 be understood that the drawing is to be considered as merely illustrative and not as defining or limiting the scope of the invention, the accompanying claims being relied upon for that purpose.

25 Of the drawing:

Figure 1 is a plan view of a chuck embodying the invention.

Fig. 2 is a cross sectional view.

A chuck embodying the invention is 30 adapted for a wide variety of uses, but it is particularly well suited for use on a grinding machine such, for instance, as that set forth in my copending application for surface grinding machines, Serial No. 247,683, filed on even date herewith. I have therefore shown in Fig. 2 a part of the frame 35 of such a grinding machine.

The grinding machine is provided with a main frame 1 having a vertical bearing 40 aperture 2. The chuck has a main bed plate 3 which is circular in outline and which is provided with a depending bearing trunnion 4 which fits the aforesaid bearing aperture 2. The bed plate 3 has connected to it a ring 5 which has sliding engagement with a bearing surface 6 of the frame 1, this bearing surface serving to support the bed plate and the parts carried thereby. Preferably the ring 5 is provided 45 on its periphery with gear teeth 7 by means of which the chuck may be turned. Preferably, as shown, the bed plate 3 has an annular groove 8 formed therein near its periphery, and into this groove there projects

a flange 9 on the frame 1. This flange projecting into the groove serves to prevent water or other foreign matter from entering the space beneath the chuck.

Secured to the bed plate 3 are segments 10 formed of steel or other magnetic material. I have shown six such segments, but it will be understood that the invention is not limited to this exact number. Formed in the top of each of the segments are several grooves which are fitted with 65 strips 11 of brass or other suitable non-magnetic material. The exact shape of the grooves and of the strips which fit them constitutes no part of the present invention. The arrangement shown in the drawing 70 is satisfactory. Below the non-magnetic strips 11 each of the segments is provided with magnetic coils which may be of any usual or preferred construction. These coils are suitably connected with collector rings 75 12 and 13 which are carried by a ring 14 of non-conductive material. The collector rings 12 and 13 are engaged by brushes 15 and 16 which are connected with a cable 17. By means of these connections electric current 80 is led to the coils in the segments 10, thus causing them to magnetize the upper surfaces in the well known manner. The construction is such that a piece of magnetic material, which is large enough to 85 engage the metal at two sides of one of the brass strips 11, will be firmly held magnetically.

Between each of the segments 10 there is positioned a strip 18 of steel or other suitable material. The top surfaces of the strips 18 are flush with the top surfaces of the segments 10. Each of the strips is arranged radially, as shown, and is suitably connected to the bed 3. Formed in each of the strips 18 is a slot 19 which is preferably T-shaped and which is preferably open at its outer end. Preferably at the center of the chuck there is provided a disk 20 which is suitably secured in place, as, for instance, by 100 means of screws 21, and which is provided with a central aperture 22.

It will be understood that in use the chuck can be used as a magnetic chuck in the usual manner. A piece of magnetic material can be laid upon any part of the chuck surface and can be magnetically held by energizing the coils of the segments 10. If,

however, it is desirable for any reason to hold the work mechanically, either in conjunction with the magnetic action or independently thereof, this can be readily effected by means of T-bolts entered in the T-slots 19. Frequently, even when the work is to be held solely by magnetic action, it is desirable to provide stops or gages to assist in properly positioning the work on the chuck. 10 These stops or gages can be clamped to the chuck by means of T-bolts engaging the T-slots 19. When necessary, the hole 22 can be used to assist in holding a stop or other fixture in place. 15 Inasmuch as the slots 19 extend radially, a T-bolt engaged in one of them can be placed at any desired position from the axis. Inasmuch as the slots are open at their ends, they can be readily cleaned should dirt and 20 débris accumulate therein. It will be seen that the several strips 18 are separate from the magnetic segments and that they are ca-

pable of being removed or renewed when necessary.

What I claim is:

1. A rotatable chuck comprising a plurality of magnetic segments and a plurality of separate and removable radial strips arranged respectively between adjacent segments, each of the strips having a longitudinal T-slot therein. 25

2. A rotatable chuck comprising a bed plate, a plurality of separate magnetic segments secured to the bed plate independently of each other, and a plurality of separate and removable radial strips arranged respectively between adjacent segments and secured to the bed plate independently of the segments, each of the strips having a longitudinal T-slot therein. 30

40 In testimony whereof, I hereto affix my signature.

BENGT M. W. HANSON.
